CLAIM

The ornamental design for an opening of an upper portion of a garment, as shown and described.

DESCRIPTION

FIGS. 1-4 show a first embodiment of a portion of an opening of an upper portion of a garment of our design; FIG. 1 is a perspective view of an entire garment, showing the opening being claimed with the opening being open of the embodiment thereof;

FIG. 2 is a perspective view of an entire garment, showing the opening being claimed with the opening being closed of the embodiment thereof;

FIG. 3 is a front elevational view with the opening being open of the embodiment thereof;

FIG. 4 is a front elevational view with the opening being closed of the embodiment thereof;

FIGS. 5-8 show a second embodiment of a portion of an opening of an upper portion of a garment of our design; FIG. 5 is a perspective view of an entire garment, showing the opening being claimed with the opening being open of the embodiment thereof;

FIG. 6 is a perspective view of an entire garment, showing the opening being claimed with the opening being closed of the embodiment thereof;

FIG. 7 is a front elevational view with the opening being open of the embodiment thereof; and,

FIG. 8 is a front elevational view with the opening being closed of the embodiment thereof.

The small broken lines along the collar depict stitching that forms no part of the claimed design. The larger evenly spaced lines depict portions of the garment that form no part of the claimed design. The larger evenly spaced lined squares in FIGS. 3-4 and 7-8 depict boundaries of the claimed design that form no part of the claimed design.

1 Claim, 6 Drawing Sheets
